Primary Examiner — Mojtaba Tehrani(74) *Attorney, Agent, or Firm* — Walter M. Egbert, III; Gerard M. Donovan; Reed Smith LLP(57) **CLAIM**

We claim the ornamental design for a rangefinder, as shown and described.

DESCRIPTION

FIG. 1 is a right side view of the rangefinder; and, FIG. 2 is a perspective view of the rangefinder of FIG. 1. Views not shown in the drawings form no part of the claimed design.

Broken lines shown in the drawings form no part of the claimed design.
